UNITED STATES PATENT OFFICE.

CLARENCE A. BERKINS, OF MINNEAPOLIS, MINNESOTA.

OIL BURNER.

Application filed October 18, 1926. Serial No. 142,395.

My invention has for its object to provide an improved oil or hydro-carbon burner adapted for general use in furnaces, boilers, stoves and the like, and is designed particularly as an improvement on the type of hydro-carbon burner disclosed and claimed in my prior Patent No. 1,499,335, issued of date July 1, 1924.

In the accompanying drawings, which illustrate a commercial form of the improved burner, like characters indicate like parts throughout the several views.

Referring to the drawings:

Fig. 1 is a plan view showing the burner with the air tube removed;

Fig. 2 is a bottom plan view of the removed air tube; and

Fig. 3 is a vertical section taken through the complete burner on the line 3—3 of Fig. 1.

The present invention differs from or is an improvement on the burner of my prior patent chiefly in the following features, to wit: The generating cone is formed integral with a supplemental bowl; the supplemental bowl is associated with and located over but spaced from an underlying bowl; the air delivery tube, at its delivery end, is provided with spiral vanes or flanges or equivalent means, whereby the air discharged around the generating cone will be caused to take a whirling motion; and the air intake tube has a detachable interlocking engagement with the seat therefor provided in the top plate of the base member of the burner.

The base member 4 of the burner is of box-like form and, by a vertical partition 5, is divided into a dead air chamber 6 and an air intake chamber 7. At its top, this box-like base is provided with a flanged cover 8 and, over the dead air chamber 6, said base is formed with an annular bowl or depression 9 having an upwardly projecting conical central portion 10. The oil delivery pipe 11, at its upper end, is threaded and screwed into the truncated top portion of the cone 10 and communicates with a short pipe section 12 that is threaded at both ends and its lower end is screwed into the cone 10 in registration with the adjacent end of the oil pipe 11. This pipe section 12, therefore, is a detachable section of the oil supply pipe.

The numeral 13 indicates the generating cone, the apex of which is perforated and

internally threaded and screwed onto the threaded upper end of the pipe section 12. This generating cone 13 is formed with an annular steps 14 of increasing diameter from the top toward the bottom of the cone, and at its lower edge, said cone is formed integral with a supplemental bowl 15 of annular form and of such dimensions that it is spaced from the lower bowl 9 so as to afford an air space between the cones 10 and 13 and between the annular bowls 9 and 15. The bowl 9, at one side and above its bottom, is provided with an overflow passage 16 from which an overflow pipe 17 leads downwardly, preferably through the air supply chamber 7. The goose-necked or curved air intake tube 18 is preferably a cast shell with its receiving leg longer than its delivery leg. The lower end of the relatively long receiving leg of this air tube is detachably seated in a large opening 19 formed in the top plate 8 above the air supply chamber 7. The extreme lower end of said leg telescopes into the opening 19 and is provided with a stop flange 20 just above the plate 8 and with a notched lock lug 21 that is engageable just below said plate 8. The lug 21 is diametrically opposite the short leg of the air tube, so that when the air tube is applied as shown in Fig. 3, the short leg of said tube will be properly positioned around the upper portion of the generating cone 13. The interlocking connection described, however, permits the air tube to be very readily lifted from working position by a sort of rocking movement and to be applied in working position by a reverse rocking movement.

The short leg of the air tube 18 is provided with overlapping spiral flanges or vanes 22 that are spaced from the steps of the cone 13, but will cause the downwardly delivered air to take a whirling motion around the cone. The supplemental bowl 15 is provided with upstanding deflecting pegs or lugs 23, which not only increase the heat-radiating surface of the bowl, but deflect the vapors in all directions and thereby insure thorough commingling of the oil vapors and air just before they pass outward of the supplemental bowl 15.

In the improved burner described, there will always be air in the space between the upper and lower bowls, and this air will act more or less as an insulation to prevent the lower bowl from becoming excessively hot,

- even when the upper cone and supplemental bowl are at very high temperatures. The oil will not, therefore, be subjected to high temperature until it is delivered onto the generating cone 13, and the said generating cone and supplemental bowl may be at very high temperatures, because the metallic conducting surface is reduced to a minimum, to wit: simply to the cross section of the pipe section 12. The air delivered with a whirling motion around the cone will sweep circumferentially over the steps thereof, which insures rapid vaporization of the oil and mixture with the air and, moreover, the whirling commingled air and oil vapors will be swept into the supplemental bowl 15 and against and between the pins or pegs 23, thereby further insuring the most thorough commingling of the oil vapors and air.
- If, by accident, the flames of the burner should be extinguished while the oil supply is still turned on, then the overflow of oil accumulated in the supplemental bowl 17 will run into the lower bowl 9 and from thence out through the overflow pipe 17. In installing this burner in the fire pot of a boiler or furnace, the base 4 will usually be placed directly on the grate bars 24 and the grate bars, outside the base, will be covered with bricks 25 or the like, so that the only air that can pass through the grate will go upward through the air chamber 7 and thence through the air tube 18.
- It will be noted that, in view of the threaded engagement between the pipe section 12

and cone, the said cone and supplemental bowl are made vertically adjustable with respect to the delivery end of the air tube and with respect to the lower bowl or base plate.

In actual practice, the efficiency of this burner has been thoroughly demonstrated.

What I claim is:

1. An oil burner comprising a base provided with an air passage and offset therefrom with an annular bowl, of an oil delivery pipe extended axially through said bowl, a generating cone supported by the upper end of said oil delivery pipe, the latter serving to deliver oil to the top of said cone, and a supplemental annular bowl formed integral with said generating cone, said generating cone and supplemental bowl being spaced from said lower bowl.
2. The structure defined in claim 1 in which said supplemental bowl is provided with circumferentially spaced upstanding deflecting lugs against and between which the commingled air and oil vapor will be directed.
3. The structure defined in claim 1 in which the lower bowl is provided with a drain passage and a drain pipe extended therefrom.
4. The structure defined in claim 1 in which said upper bowl and cone are vertically adjustable with respect to said lower bowl and the delivery end of said air pipe.

In testimony whereof I affix my signature.

CLARENCE A. BERKINS.
